UNITED STATES PATENT OFFICE.

ALPHONSE THEYSKENS, OF TESTELT, BELGIUM.

FRICITION-BRAKE FOR WINDOW-SASHES.

1,366,972.

Specification of Letters Patent.

Patented Feb. 1, 1921.

Application filed July 19, 1920. Serial No. 397,333.

To all whom it may concern:

Be it known that I, ALPHONSE THEYSKENS, manufacturer, a citizen of the Kingdom of Belgium, and resident of Testelt, Belgium, have invented certain new and useful Improvements in Friction-Brakes for Window-Sashes; and I do hereby declare the following to be a full, clear, and exact description of the invention, such as will 10 enable others skilled in the art to which it appertains to make and use the same, reference being had to the accompanying drawings, and to letters or figures of reference marked therein, which form a part of this 15 specification.

The present invention relates to a friction brake capable of being utilized for the wedging of window sashes, in a determined position, while permitting easy displacement of the parts.

This result is obtained according to a device previously known by the employment of two brake shoes arranged on both sides of the part on which friction is operative 25 and constantly urged by a spring or by gravity to approach one another to effect the locking, unlocking being obtained by means of devices producing a separation of the shoes when they are actuated by hand 30 or when they meet appropriate abutments after a certain displacement.

According to the present invention, in the case of a window sash for a railway carriage door the two brake shoes form two vertical 35 sides of a deformable parallelogram suspended from above and in the interior of which is compressed the sash to be wedged up.

The drawing shows by way of example 40 different forms of carrying out the invention.

Figure 1 is a front view of the window frame, Fig. 2 is a section of the line A, B of Fig. 1, Fig. 3 a section on a larger scale 45 on line C—D of Fig. 1. Figs. 4 to 7 show details on a larger scale.

The frame of the sash 1 is surrounded by a pivoted parallelogram composed of two brake shoes 2 and 3 which are intended 50 to bear frictionally or rub directly upon the frame 1 and by the cross-pieces 4. The parallelogram is suspended at one of its angles by means of two springs 5 and 6, the first of which is attached to a lever 7 55 pivoted at 8 to some stationary point and at 9 to a shoe 3 while the second is attached

to a lever 10, one end of which is pivoted at a fixed point while the other is located beneath a button 11 of the shoe 3.

The parallelogram being suspended at 60 the top tends to lose its form under the action of its own weight; which may be partially counterbalanced by a spring 12, and to wedge the frame 1 between its sides 3 and 2 forming brake shoes. Upon operating the frame 1 from the top downward it descends carrying along with it the whole parallelogram, against the action of the suspensory springs, until the moment at 65 which the shoe 2 encounters a rigid abutment 13; the shoe 3 continues the movement alone which causes the deformation of the parallelogram thus permitting a sliding movement of the frame; the frame then descends alone sustaining a frictional braking 70 action produced by the springs 5 and 6. As soon as action upon the frame 1 is ceased, the parts automatically resume the wedging position. If on the contrary an effort from the bottom upward be exerted 75 upon the frame 1, the parallelogram is also dragged along until the shoes come in contact with the abutment 14; then the frame will only carry along the shoe 2 and the 80 unlocking effect is produced as in the preceding case, the braking effect being in this case regulated by the weight of the parts, 85 partially balanced by the spring 12. During the ascent of the parallelogram the action of the spring 6 is cut off at the end 90 of a certain space of time by the abutment of its lever 10 against a button 15.

The combined action of the springs 5 and 12 may be replaced by the action of a single spring, the strength of which is equal 95 to the sum of the two springs 5 and 12, and is applied at a suitable point of one of the cross-pieces 4.

In the form of the construction according to Fig. 3 the frame 1 carries an iron 100 facing 16 engaging between two plates 17 of the frame of the window and carrying a friction device of wood, fiber, etc., 18; the brake shoes have then the form of a U-shaped piece of iron.

The guiding of the parallelogram is completed by levers such as 19 having the same length as lever 7 and by rods or bars 20 provided at their two ends with ball and socket joints in the brake shoes 2 or 3 and 110 the fixed frame 21 of the window (Figs. 2 and 5).

This stationary or fixed frame 21 carries at its lower part a gutter or channel 22, Figs. 2 and 6; the slot requisite for the passage of the frame is formed by a plate with a pivotal spring 23 conducting the water into the gutter or channel 22.

In the form of the construction according to Fig. 7 the shoes 2 and 3 carry arms, upon which there act two buttons 24 made in one 10 with a lever not shown, which permits of the release of the shoes; this arrangement is used when a powerful braking effect is desired.

What I claim is:

15 1. A frictional brake device for the window sash of a door, comprising a pivoted parallelogram surrounding the sash, the two vertical sides of said parallelogram forming the brake shoes, means for suspending the parallelogram at one of its apexes to the door by the aid of springs, a fixed abutment upon the door above the suspension apex of the parallelogram and another fixed abutment beneath the opposed apex of the parallelogram.

20 2. A frictional brake device for the window sash of a door, comprising a pivoted parallelogram surrounding the sash, the two vertical sides of said parallelogram forming the brake shoes, means for suspending the parallelogram at one of its apexes to the door by the aid of two springs, one of which 25 has an action restricted to the lower portion of the upward movement of the suspension apex, a fixed abutment upon the door above the suspension apex of the parallelogram

and another fixed abutment beneath the opposed apex of the parallelogram.

3. A frictional brake device for the window sash of a door, comprising a pivoted parallelogram surrounding the sash, the two vertical sides of said parallelogram forming the brake shoes, and being U-shaped so as to guide the sash, means for suspending the parallelogram at one of its apexes to the door by the aid of springs, a fixed abutment upon the door above the suspension apex of the parallelogram and another fixed abutment beneath the opposed apex of the parallelogram.

4. A frictional brake device for the window sash of a door, comprising a pivoted parallelogram surrounding the sash, the two vertical sides of said parallelogram forming the brake shoes, means for suspending the parallelogram at one of its apexes to the door by the aid of springs, a fixed abutment upon the door above the suspension apex of the parallelogram and another fixed abutment beneath the opposed apex of the parallelogram and a spring attached to that vertical side of the parallelogram that is not connected to the suspension apex, for the purpose of partially counterweighting the weight of the parallelogram.

In testimony whereof I affix my signature in presence of two witnesses.

ALPHONSE THEYSKENS.

Witnesses:

LOUIS TRETS,
Jos. LAURTIEN.
